To all whom it may concern:

Be it known that I, Max Salee, a citizen of the United States of America, residing at New York, in the county of New York and State of New York, have invented a new, original, and ornamental Design for a Marking Paper for Tailors' Use, of which the following is a specification, reference being had to the accompanying drawing, forming part thereof.

The marking paper is of no appreciable thickness, being merely a sheet of paper having the design printed thereon.

I claim:

The ornamental design for a marking paper for tailors' use, as shown and described.

MAX SALEE.
